U.S. Appl. No. 29/449,432, filed Mar. 15, 2013, Hughes et al.

Primary Examiner — T. Chase Nelson*Assistant Examiner* — Michelle E Wilson(74) *Attorney, Agent, or Firm* — Ntellect Law, P.C.(57) **CLAIM**

The ornamental design for a mop head, as shown and described.

DESCRIPTION

FIG. 1 is a top, right side, perspective view of a mop head showing our new design;

FIG. 2 is a bottom, right side, perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in FIGS. 1-8 illustrate portions of the mop head that form no part of the claimed design.

1 Claim, 7 Drawing Sheets(56)
